UNITED STATES PATENT OFFICE.

JOHN DICKENS, OF PASSAIC, NEW JERSEY.

AIR-PUMP.

982,660.

Specification of Letters Patent. Patented Jan. 24, 1911.

Application filed November 4, 1908. Serial No. 461,061.

To all whom it may concern:

Be it known that I, JOHN DICKENS, a citizen of the United States, residing at Passaic, in the county of Passaic and State 5 of New Jersey, have invented new and useful Improvements in Air-Pumps, of which the following is a specification.

My present invention relates to improvements in air pumps and especially to that 10 class adapted for the inflation of pneumatic tires or for other purposes, and it has for its object to provide an improved pump of this character which is comparatively simple and inexpensive in its construction and 15 which in operation is capable of compressing at each stroke of the piston or plunger a quantity of air or other fluid of a volume greater than that which is ordinarily compressed at each stroke of pumps of the usual 20 construction, a compound compression of the air being accomplished although the pump may contain a single cylinder and piston, a pump being thereby provided which has a relatively large capacity al- 25 though it is relatively small or compact and its construction is simple, containing as it does a few parts which are not liable to get out of order or require frequent repairs.

To these and other ends, the invention 30 consists in certain improvements, and combinations and arrangements of parts, all as will be hereinafter more fully described, the novel features being pointed out particu- 35 larly in the claims at the end of the specification.

In the accompanying drawing, Figure 1 represents a longitudinal section of an air pump constructed in accordance with my invention; Fig. 2 represents a transverse 40 section of the pump on the line 2—2 of Fig. 1; and Figs. 3 and 4 are perspective views of the elements of the upper air valve.

Similar parts are designated by the same 45 reference characters in the several views.

Pumps constructed in accordance with my present invention are capable of use for various purposes, and in the accompanying drawing, I have shown one specific embodiment of the invention which is especially adapted for the inflation of pneumatic tires or for similar purposes in which cases, a relatively small pump of large capacity is desirable. It will be understood, 50 however, that the invention is not limited to the specific embodiment shown, as cer-

tain modifications in the construction and arrangement of the parts may be made in order that the invention may be applied to the best advantage in each particular 60 case.

In the present instance, the pump comprises a cylinder 1 of a suitable length and diameter, the lower end of this cylinder being threaded or otherwise fitted tightly 65 into a base 2, the latter being formed of a casting or otherwise and it preferably has a pair of lateral extensions which form a pair of foot rests 3 upon which the feet of the operator may rest during the operation 70 of the pump. A piston or plunger 4 is mounted to reciprocate axially of the cylinder and it is operable by a piston rod 5, the upper end of which may be provided with a suitable handle 6 by means of which 75 the piston may be reciprocated. A cap 7 is threaded or otherwise tightly fitted upon the upper end of the cylinder and has a stuffing-box 8 through which the piston rod operates, the stuffing-box preventing the 80 escape of air around the piston rod during the upward or return strokes of the piston. A double-acting piston is employed in the present instance, and while a piston of any 85 suitable construction may be employed which is capable of compressing air upon both sides, I prefer to employ a piston having a pair of cup-shaped packing washers 9 and 10, these packing cups being firmly clamped by the nuts 11 and 12 against the upper 90 and lower sides of the piston and they are arranged in reverse relation so that upon the up-stroke of the piston, the upper packing cup will compress air in the upper portion 95 of the cylinder while a down-stroke of the piston will cause the packing cup 10 to compress air in the lower portion of the cylinder.

An air inlet 13 is formed in the base and it communicates with the space at the 100 bottom of the cylinder. A check valve is provided which permits air to enter the lower end of the cylinder through the air inlet and it prevents discharge of air through the inlet. A check valve of any suitable construction may be employed, that shown in the present instance comprising a ball 14 which is acted upon by a spring 15 which normally tends to seat it and thereby close the air inlet. An apertured bushing 16 may 105 be threaded or otherwise fitted into the base and this bushing co-operates with the spring 110

and by adjusting the bushing the tension of the spring may be adjusted. By removing the bushing, the spring and the ball-valve are rendered accessible. A discharge 17 is also formed in the base and may be connected by the nipple 18 to the device which is to be supplied with the compressed air. In using the pump for the inflation of pneumatic tires, the usual flexible tube may be attached to this nipple, and the check valve of the tire in such instances, serves as a check valve for the discharge passage of the pump. Air is also admitted to the upper portion of the cylinder through an inlet 19 which is preferably formed in the cap 7, and this inlet is also controlled by a suitable check-valve whereby air may be admitted to the upper portion of the cylinder through this inlet, but it is prevented from escaping therethrough. In the present instance, a check-valve is employed which consists of a disk 20 of leather, rubber or other material which is preferably flexible and this disk has a central aperture 21 through which the piston rod passes loosely. This disk coöperates with a flat surface 22 which is formed at the under side of the cap 7 and serves as a valve seat, and when the disk is in a position to open the inlet 19 and permit entrance of air to the upper portion of the cylinder, the disk then rests upon a supporting disk 23, the latter being of a diameter preferably greater than that of the valve disk 20 and it rests upon the top of the tube which forms the air cylinder. A suitable number of recesses 24 are formed preferably in the periphery of the supporting disk 23 so as to permit air to pass around the valve disk and through these recesses into the upper portion of the cylinder. The piston rod also passes loosely through a central aperture 25 formed in the disk 23.

During the operation of the pump, as will hereinafter appear, air passes from the upper to the lower side of the piston, and in the present instance, the piston rod 5 is provided with a by-passage 26 which extends upwardly from the lower end of the piston rod and in a direction axially thereof, and this axial passage communicates with the space above the piston through a vent 27. A valve chamber is formed in the lower end of the piston rod and contains a suitable check-valve which will permit air under appropriate pressure to pass from the upper to the lower side of the piston during the up-stroke of the latter. The check-valve shown in the present instance consists of a ball 28 which seats against the valve seat 29 surrounding the axial passage 26, and a spring 30 serves to retain the ball in coöperative relation with its seat. This spring is loaded heavier than the spring 15 of the inlet valve, and this may be accomplished either by making the spring 30 of heavier material or

by adjusting it under a greater tension by means of a bushing 31 which is threaded into the lower end of the piston rod and bears against the spring, this bushing being apertured to permit the passage of air therethrough. 70

In operating a pump constructed in accordance with the present embodiment of my invention, it will be assumed that the nipple 18 of the pump is connected by a tube or 75 other suitable means to a tire or other device having a check or non-return valve. As the piston rises from its lowermost position in the cylinder, a supply of air will enter the lower end of the cylinder through the 80 inlet, the check valve thereof opening due to the vacuum pressure beneath the piston. This same upward movement of the piston causes the air in the upper portion of the cylinder to be compressed, the valve disk 20 85 rising so as to close the inlet 19. When the body of air in the upper portion of the cylinder is compressed sufficiently to overcome the pressure of the spring 30 which retains the valve 28 upon its seat, this valve will 90 open, allowing the compressed air in the upper portion of the cylinder to pass the piston and enter the lower portion of the cylinder, the valve 14 of the inlet closing, and the remaining portion of the upward 95 or return stroke of the piston serves to transfer the air from the upper to the lower portion of the cylinder. Upon the down-stroke of the piston, the valve 28 will close under the pressure of air in the lower portion of 100 the cylinder and, as the piston descends, the body of air in the cylinder will be forced out through the discharge passage 17. During the descending movement of the piston, the valve disk 20 will leave the valve-seat 22 105 so as to rest upon the supporting disk 23, the inlet 19 being thereby opened so that air enters the upper portion of the cylinder therethrough.

A pump constructed in accordance with 110 my present invention is capable at each power stroke of the piston of compressing a volume of fluid greater than that which would be drawn into the cylinder during each stroke of an ordinary single-acting 115 pump, as a part of the air or other fluid behind or above the piston is compressed and is introduced into the cylinder at the compression side of the piston during each return stroke thereof and such air is given a second compression during its discharge 120 from the pump. The result is that the capacity of the pump is increased without enlarging its dimensions, thus providing a pump which is admirably adapted for use 125 in the inflation of pneumatic tires or in other connections where the pump is essentially portable, such for instance as where the pump is used as a part of the equipment of an automobile. Moreover, 130

the pump is not only compact in its dimensions, but it is comparatively simple in its construction, as a compound compression of the air is practically effected, al-

5 though a single cylinder and piston only is used, and the arrangement of the various working parts of the pump is such that they are not liable to injury.

I claim as my invention:—

10 1. A pump comprising a cylinder, valves for admitting air alternately to the opposite ends thereof, a piston reciprocable in said cylinder and capable of introducing and compressing air at both sides thereof

15 whereby a body of air introduced into one end of the cylinder is compressed during one stroke of the piston, and means for introducing a body of air into the opposite end of the cylinder while the body of air

20 in advance of the piston is being compressed and for transferring the body of compressed air in advance of the piston to the rear side of the piston when the compression of such body of air reaches a predetermined point

25 during the stroke of the piston, the next stroke of the piston causing a recompression of both bodies of air.

2. A pump comprising a cylinder, a reciprocatory piston capable of introducing

30 and compressing air at both sides thereof, valves for admitting air alternately to the opposite ends of said cylinder, and means for introducing a body of air compressed at one side of the piston to the opposite side

35 thereof and for causing a second compression of such air.

3. A pump comprising a cylinder, a reciprocatory piston having a passage through it and a valve for permitting air to be transferred from one to the other side of the piston through said valve, means for introducing and compressing air at both sides of said piston, and means for causing air to be introduced into the space at one

45 side of said piston partially from the atmosphere and partially through said passage from the space in advance of the piston while the piston moves in one direction.

4. A pump comprising a cylinder, a reciprocatory piston capable of receiving and compressing air at both sides thereof and having a passage therethrough controlled by a loaded valve, and means for causing a volume of air to be introduced from the atmosphere in rear of said piston during a portion of its stroke and for transferring air compressed in advance of said piston during such stroke into the space in rear thereof to effect a compound compression

55 of the air while said piston moves in one direction.

5. A pump comprising a cylinder, a reciprocatory piston, check valves for admitting air alternately to the opposite ends of

60 the cylinder, and means for transferring

air compressed at one side of the piston to the space in rear thereof after a quantity of air has been drawn into said space from the atmosphere.

6. A pump comprising a cylinder, a reciprocatory piston, check valves for admitting air alternately to the opposite ends of the cylinder, and a check valve for transferring air compressed at one side of said cylinder to the space at the opposite side thereof after said piston has traversed a portion of its stroke in one direction and has drawn into the space behind said piston a quantity of air from the atmosphere.

7. A pump comprising a cylinder, a reciprocatory piston, a discharge being provided at one end of said cylinder, an air inlet valve arranged at the same side of the cylinder with said discharge, a check valve for admitting air to the opposite end of the cylinder, a by-passage between the two sides of the piston being formed in the piston, and a check valve held closed with a force sufficient to insure the opening of said by-passage to admit compressed air from the forward side of the piston to the space at the discharge end of the cylinder after the piston has traversed a portion of its return stroke.

8. A pump comprising a cylinder, a reciprocatory piston, check-controlled inlets for admitting and causing compression of air at opposite sides of said piston during its operation, a by-passage being formed in the piston and communicating with the opposite sides thereof, and a check-valve capable of opening to permit air to be transferred from one to the other side of said piston after the latter has traversed a portion of its stroke in one direction.

9. A pump comprising a cylinder, a reciprocatory piston having air inlet valves at opposite ends and a discharge passage at one end, a by-passage being formed in the piston and communicating with the spaces at opposite sides thereof, and a check-valve controlling said by-passage and arranged to open toward that end of the cylinder provided with the discharge passage, said check-valve being provided with a spring of a strength sufficient to retain it in closed position until after the piston has traversed a portion of its stroke whereby a volume of compressed air will be transferred from one to the opposite side of said piston preparatory to a secondary compression and discharge thereof.

In testimony whereof I have hereunto set my hand in presence of two subscribing witnesses.

JOHN DICKENS.
